CONTAINER END

Raymond Luscombe Batchelor, Westwood, Carl William Heinle, Short Hills, and Leonard Thomas Lacroce, Paramus, N.J., assignors to American Can Company, New York, N.Y.

Filed Jan. 16, 1970, Ser. No. 20,947

Term of patent 14 years

Int. Cl. D9—02

U.S. Cl. D9—255

Fig. 1

Fig. 2

FIG. 1 is a top plan view of a container end showing our new design; and

FIG. 2 is a side, sectional view of the container end, taken along line 2—2 in FIG. 1.

We claim:

The ornamental design for a container end, substantially as shown.
